LOCKING MECHANISM FOR VENETIAN BLINDS

Charles D. Walker, New York, N. Y., assignor to
John M. Nordstrom, New York, N. Y.

Application December 19, 1935, Serial No. 55,182

4 Claims. (CL. 156—17)

My invention relates to the control of window shades or curtains of the "Venetian blind" type, and particularly to the cord locking means therefor.

Window shades or curtains of this type are usually operated by means of a pair of cords, whereby the shade is raised, lowered or maintained in an intermediate position, as desired. The usual devices for effecting the gripping and holding of the cords in these different positions have proven undesirable, either for their noisiness and slowness in action, or for their non-positiveness in gripping the cords. It is, therefore, an object of my invention to provide a cord holder which will be simple, silent, positive and speedy, which will comprise few movable parts, and which will be long-lived in action.

In the ordinary devices of this character, the surfaces between which the gripping and holding actions are effected are usually metallic, and are grooved, scored, corrugated, or otherwise treated, to catch and lock the cords therebetween. Constant friction frays, cuts and otherwise so injures the cords as to greatly shorten their useful life. It is, therefore, a further object of my invention to provide a device of the character described, the surfaces of the gripping and holding members of which are of yieldable and resilient material, whereby the cords are not injured, even after extraordinary use.

It is a further object of my invention to provide a device of the character described the parts of which may be easily, quickly and inexpensively replaced when occasion demands.

Other objects will in part be pointed out hereinbelow, and in part be apparent from the following drawing and description of an illustrative embodiment, in which drawing

Fig. 1 is a perspective view of a portion of a conventional "Venetian blind" provided with one form of device constructed according to and embodying my said invention;

Fig. 2 is a longitudinal section of the device substantially as same is shown in Fig. 1;

Fig. 3 is a section on the line 3—3 of Fig. 2; and

Fig. 4 is a section on the line 4—4 of Fig. 3. Broadly, my invention consists of passing the cords (shade actuating means) between relatively movable blocks faced with a resilient material, whereby as the blocks move along a determined path, the cords are quickly gripped and firmly held therebetween.

The "blind" 10 is actuated by a pair of cords

12, connected at one end 14 to the "blind" 10 itself, and free at the other end 16 for manual actuation. Cords 12 pass through holder 18 wherein they are held or released, as desired.

The casing 20 of holder 18, within which the 5 movable blocks are contained, is otherwise hollow, and comprises a pair of sheets of light gauge metal, stamped or bent to form roughly a four-sided oblique truncated pyramid; one wall 22 of which is straight and is provided with an end 10 portion 24 at an angle therefrom and an extension whereby the holder is attached to the "blind." The wall 26, opposite wall 22, is the base part of a U-shaped clip which is spot welded, or otherwise secured to wall 22, to complete the casing, 15 and this U-shaped member is so shaped that wall 26 is inclined with respect to said wall 22. The pyramid is composed of two sheets, one of which forms three sides thereof, and the other the fourth side and means to attach said casing to 20 the "blind."

A solid rectangular block 28, of resilient material, preferably hard rubber, is fastened within a U-shaped shoe 30, of light gauge metal. This shoe 30, with block 28 therein, is fitted within 25 casing 20 and secured to wall 22 thereof by means of threaded screws 32. Block 28 is so fastened within shoe 30, and shoe 30 so secured within casing 20, as to leave one face 33 of block 28 completely uncovered and open. Another block 34, 30 of similar material to block 28, is fastened within another U-shaped metal shoe 36, and also fitted within casing 20.

Block 34, while solid, is shaped like an oblique and truncated four-sided pyramid. Face 38 35 thereof, opposed to face 33 of block 28, is perfectly straight, but the face 40 thereof, abutting against shoe 36, is angled with respect thereto, just as casing wall 26 is angled with respect to wall 22.

Wall 26 is provided with a longitudinal slot 42 in the center thereof, and block 34, unlike block 28, which is fixed within the casing, is 40 slideable up and down along the track formed in wall 26 by means of the headed bolt 44 passing 45 through slot 42 and screwed into shoe 36.

The device operates as follows: Cords 12 pass from the blind 10 over pulley 46 and between the opposing block faces 33, 38, which are normally spaced apart to leave adequate clearance for the 50 cords. When it is desired to raise "blind" 10, cords 12 are merely pulled downwardly. This downward pull will be opposed only by the weight of the "blind", since the clearance between the blocks is enough to keep the cords out of contact 55

therewith. When it is desired to anchor the "blind" in any desired position to which it has been raised, cords 12 are pulled to one side to engage face 38 of the movable block. Keeping 5 the cords in the pulled over and block engaging position, as shown in dotted lines in Figures 1 and 2, the weight of the "blind" is allowed to pull the cords upwardly, carrying with them block 34. As block 34, within shoe 36, rides up the 10 track formed by slot 42 within wall 26, opposed block faces 33 and 38 are brought nearer and nearer to each other, decreasing the normal clearance until cords 12 are firmly and securely gripped and held therebetween. The dotted line 15 outline of Fig. 2 shows how short is the distance block 34 must ride up within the casing before the cords are locked, and how quickly this is accomplished. The resilient nature of the blocks and the firm grip of the cords insure the positiveness 20 of the holding and locking action, and prevent any sliding or slipping. The weight of the "blind" will continue to exert sufficient upward pull on the cords to keep the block together and prevent any back sliding on the part of block 34.

25 When it is desired to lower the shade, cords 12 are pulled downward carrying therewith block 34. This releases the block 34, which thereupon, gravity-impelled, slides to the bottom of the slot, bolt 44 serving as a stop means. Normal clearance being re-established, cords 12 will pass between the opposed blocks freely and as quickly as may be desired, in either direction, and the shade may be lowered or raised, etc.

30 I have referred to the curtain actuating means 35 as "cords"; and same may be either of fibrous material, as hemp, flax, etc. or metallic, as a link chain, both being suitable for use with my locking device.

35 I have described and illustrated but one embodiment of my invention, showing one block 40 stationary and the other block movable. However, I can make both blocks movable within the casing by providing block 28 with a headed bolt similar to bolt 44, passing through a slot in wall 22 just as block 34 rides up and down wall 26. Just as easily, the walls may each be inclined 45 with respect to the other, and the blocks, of course, correspondingly shaped. All these, and other modifications may be resorted to without departing from the spirit of my invention, the 50 gist and heart of which is the use of blocks of resilient material to effect the locking action.

55 It will be seen that my invention is quick, silent and positive in action, will not injure the cords in any manner whatsoever, can be taken down and new parts replaced very easily and quickly, and will be long lived in action, with very few parts capable of getting out of order.

60 It is adaptable for use not only to "blinds" 65 per se but to ordinary window curtains or shades, and the use of the term "shade" in my claims is not to be construed as any limitation of the uses to which my device may be put.

Having now described my invention, what I 65 claim and desire to secure by Letters Patent is:

70 1. In combination, a blind, cords to raise and lower same, and a device for locking the cords to secure the blind in any position, said device comprising a hollow casing having a pair of opposite walls upwardly inclined to each other, a pair of blocks of resilient material disposed within said casing, one of which is rideable up and down in sliding contact with one of the walls, said blocks being normally gravity maintained in the lowermost position sufficiently

apart to allow free passage of the cords therebetween, and means to cause one of said blocks to ride up its walls to decrease the normal distance between the blocks to grip and lock the cords therebetween as same approach each other, 5 said means comprising an engagement between the cord and said block whereby the weight of the blind will come into play to raise said block.

2. In combination, a blind, cords to raise and lower same, and a device for locking the cords 10 whereby to secure the blind at any position, said device comprising a hollow casing having a pair of opposite walls upwardly inclined to each other, a pair of blocks of resilient material disposed within said casing, one of which is slideable up 15 and down along one of said walls, and the other of which is the same height as the opposite wall and immovably secured thereto, said blocks being normally gravity maintained sufficiently apart to allow free passage of the cords therebetween 20 when the movable block thereof is in the down position, and gripping and locking the cords therebetween upon movement of said movable block up its inclined wall whereby the distance between the blocks is decreased.

25 3. A device of the character described comprising a hollow casing, one plane wall of which is straight and an opposite wall of which is upwardly inclined with respect thereto, a pair of 30 shoes disposed within the casing, each of which shoes has a block of resilient material mounted therein, one of said blocks being substantially 35 rectangular and disposed within one shoe against the straight wall, and the other of said blocks having one straight face and an opposite face inclined thereto similarly to the casing walls, said other block being disposed within its shoe so that the straight face is presented toward the first described block, with the inclined face of 40 said other block disposed within its shoe against and movable therewith up and down the inclined wall, said shoes and blocks being normally gravity spaced apart a distance to allow passage of shade actuating means therebetween, and being 45 relatively movable to decrease the space therebetween to grip and lock said actuating means therebetween.

50 4. A device of the character described comprising a hollow casing, one plane wall of which is straight and an opposite wall of which is upwardly inclined with respect thereto, a slotted opening in said inclined wall, a pair of shoes disposed within the casing, one of which shoes is 55 fixed within the casing, and the other of which is movable relative thereto, each of which shoes has a block of resilient material mounted therein and the movable shoe has a headed pin extending through the slot in the casing, the block in the one of said shoes being substantially rectangular and disposed within the shoe against the straight wall, and the block in the other of said shoes having one straight face and an opposite face inclined thereto similarly to the casing walls, said other block being disposed within the shoe so that the straight face is presented 60 toward the first described block, and the inclined face of said other blocks abuts against and is movable with its shoe up and down the inclined wall along the slotted track, said shoes and blocks being normally gravity spaced apart a 65 distance to allow passage of shade actuating means therebetween, and being relatively movable to decrease the space therebetween to grip and lock the actuating means therebetween.
